UNITED STATES PATENT OFFICE.

ELMER L. SCHUMACHER, OF SOUTHBIDGE, MASSACHUSETTS, ASSIGNOR TO AMERICAN OPTICAL COMPANY, OF SOUTHBIDGE, MASSACHUSETTS, A VOLUNTARY ASSOCIATION OF MASSACHUSETTS.

OPHTHALMIC MOUNTING.

Application filed August 30, 1919. Serial No. 320,899.

To all whom it may concern:

Be it known that I, ELMER L. SCHUMACHER, a citizen of the United States, residing at Southbridge, in the county of Worcester and State of Massachusetts, have invented certain new and useful Improvements in Ophthalmic Mountings, of which the following is a specification.

This invention relates to improvements in 10 ophthalmic mountings and has particular reference to an ophthalmic mounting formed from suitably combined or united metallic and non-metallic members.

Previous to my invention numerous attempts have been made to produce mountings of the character above referred to, by either clamping the metal onto the zylonite, placing split zylonite or non-metallic tubular members around metal parts and securing 20 them by clamps, screws, rivets or the like, and attempts have been made at embedding the metal in strip stock and then the parts subsequently formed into the complete mounting. All of these prior art constructions, 25 however, have met with certain difficulties in construction and have presented certain unsatisfactory features in their final embodiment due to the character of zylonite and similar non-metallic materials, in that it has 30 considerable tendency toward expansion and contraction, will not properly hold its shape under varying heat conditions, and is relatively frangible while quite inflammable. The attachment by large clips or the like 35 when the device is for use on an ophthalmic mounting, is unsightly. The attachment by rivets, screws, or the like, necessitates the piercing of the non-metallic material with consequent weakening and possibility of 40 breakage. The prior embedment of a wire or the like for reinforcement purposes, renders it impossible to properly attach the other fittings by soldering on account of the inflammability of the material and the partial embedment only of a reinforcement leaves the 45 nonmetallic material free to expand and contract, with the consequent disadvantages.

It is, therefore, the purpose of my present invention to provide an improved construction which will eliminate all the defects present in the prior art constructions and provide an improved form of ophthalmic mounting in which an entire metallic frame soldered together or united in the regular man-

ner may be employed, and in which the desired portions of such frame may be equipped with a zylonite or other non-metallic coating or covering which shall be strong, durable and attractive in appearance and will securely remain in place without the use of separate additional or unsightly attaching members, and which will possess advantages in appearance and durability over the dipped type of mountings which have in the past been experimented with.

A further object of the present invention is the provision of a novel and improved process or production of the article in question.

Other objects and advantages of my improved construction should be readily apparent by reference to the following specification taken in connection with the accompanying drawings, and it will be understood that I may make any modifications in the specific details of construction shown and described within the scope of the appended claims without departing from or exceeding the spirit of my invention.

Figure I represents a front view of a mounting embodying my improvements.

Figure II represents a sectional view thereof as on the line II-II of Figure I.

Figure III represents a view partially in section of a temple construction embodying my improvements.

Figure IV represents a longitudinal sectional view of a frame or temple wire embodying certain of my improvements.

Figure V represents a view in plan and section of a strip of material for use in covering my improved frame.

Figure VI represents a similar view of the same formed into a tube.

Figure VII represents a sectional view of a split tube member initially applied to an ophthalmic frame.

Figure VIII represents a view of the same grasped by the forming dies.

Figure IX represents a view of the non-metallic tube held between the several forming or shaping dies to properly fit the frame.

Figure X represents a plan view of the parts shown in Figure IX.

Figure XI represents a view of a slightly modified manner of forming my improved construction.

Figure XII represents a plan view of a

final step in the method or process illustrated in Figure XI.

In the drawings, the numeral 1 designates the metal bridge of an ophthalmic mounting having soldered to each end thereof the grooved eye wire member 2 adapted to receive the lens, these eye wire members being split at their outer sides and having their ends connected together as by the end pieces 3 which also serve as points of attachment for the pivoted temple butts 4 which are provided with the portions 5 adapted to fit behind the ear of the wearer and retain the mounting in position on the face.

15 The construction of frame just described is that ordinarily employed in all-metal frames, possessing the desired rigidity of parts and the frame wires being grooved for the reception of lenses.

20 I have found, however, that certain advantages reside in the coating of the exposed part or parts of the metallic frame with a non-metallic composition, such as celluloid, which will have a softer feeling where contacting with the face, which is impervious to the acid effects of perspiration or the like, liable to cause discoloration of gold-filled or similar metal frames, and which forms a slightly softer material for mounting of the lenses, lessening the liability of breakage of same.

25 As previously mentioned, prior to my invention numerous attempts have been made to satisfactorily obtain a structure of this nature, but all have been open to objection either from appearance or durability, or both.

30 In the carrying out of my present invention, however, I am able to cover any or all parts of the frame after it has been soldered together and the several metal parts permanently united, and am able to place on these metal parts a non-metallic covering which will be firmly held in place without additional fastening members, which will present an extremely neat and attractive appearance, which will provide a satisfactory mounting for the lenses and properly protect the face of the wearer from contact with metallic parts.

35 In the accomplishment of this result I may if desired make use of sheet stock 6, as illustrated in Figure V, Figure V showing a blank of stock adapted for the formation of an eye wire having at one side the notch 7 to receive the end 8 of the bridge 1, so that the stock may pass around the bridge and down onto the eye wire. The material having been cut in sheet form, may then be pressed up into the split tube 9 illustrated in Figure VI, which may be entirely closed, as illustrated, or only partially closed. A further step may include the coating of the eye wire or other part 2 with a layer of glue, shellack or suitable cement 10, after which

the tube or portion or stock 9 is placed snapped or sprung around the outer face of the frame 2.

40 The parts are then introduced between the separable die members 11 which are suitably heated to transmit heat to and soften the stock of the member 9, the two dies being brought together to clamp the stock firmly against the frame 2 and cause it to curve inwardly toward the center as illustrated in 45 connection with Figure VIII. The inwardly curving portions are engaged by the former 12, which is pressed thereagainst until it reaches the position shown in Figure 50 IX, when the inner part of the stock will 55 be pressed tightly against the groove of the frame and will itself form a lens receiving groove, the joint being secured by the cement 10 extruded from the groove in the metal by the pressure of the ends of the 60 non-metallic covering thereagainst. The pressure here applied and the control of the heat is such that the coating will be firmly secured to the entire frame and satisfactorily remain thereon when the frame is 65 moved from the dies.

70 This forming step may be either with the frame in partially rounded condition, as illustrated in connection with Figure X, which shows a plan view of the dies and 75 parts, or may be in the form of a roller former 13 carried by the rotating arm 14 on the stud 15 which is mounted on one of the dies and serves to roll down the material in circular form. In either event, I prefer, through the use of suitable die members 80 11, to clamp the frame securely around the sizer plate 16, heating the sizer plate so that the celluloid may yield sufficiently to 85 exactly conform to the size of the plate.

90 In this manner the interior diameter of the lens receiving groove 17 in the celluloid will be to exact standard size so that a stock standard lens will accurately fit, while the securing of the zylonite or celluloid 9 to the frame 2 is such as to prevent all expansion or contraction of the material in question so that the size will be 95 accurately maintained as well as the parts remaining in place. If desired to assist in the retention of the covering 9 on either 100 frames, bridges or temples, I may form the metallic parts with the grooves, channels or recesses 18 into which the cement and celluloid, or celluloid alone, if cement is not 105 employed, will be pressed, while under the influence of heat in the forming dies to insure a more secure interlocking of the parts.

110 The particular importance of the sizer 125 plate 16 resides in the fact that edged lenses as commercially sold and machines for edging prescription lenses are constructed to certain standards, and in order that a lens be properly held within a frame so that 130

the frame will tightly hold the lens in place and prevent turning or the like, which is very injurious, particularly in connection with cylindrical lenses, it is necessary that 5 the interior diameter of the frame or lens receiving groove correspond exactly with the exterior diameter of the lens. It must neither be too tight a fit, causing a gap at the joint or end piece, or too loose, allowing the lens to slip. I, therefore, construct 10 my sizer plate 16 of the exact correct size for the particular frame to be constructed and draw or squeeze the frame around the former by the die members 11 so that the 15 former provides the exact correct size of groove to receive the lens so that a standard size lens may be readily inserted in the frame or such lenses interchangeably placed in the frame as desired, eliminating the 20 necessity of specially fitting the individual lens to the individual frame, which has been a difficulty experienced in the past in connection with prior art forms of non-metallic lens receiving rims.

25 I claim:

1. The process of placing a non-metallic covering on a grooved metallic eye wire, consisting in forming the non-metallic covering from sheet stock into a split tube, 30 coating one of the parts with an adhesive, applying the split tube to the eye wire, compressing the tube onto the eye wire and into the groove with heated dies to insure proper union of the parts, and stretching the 35 combination frame about a sizer plate to insure correct sizing of the interior lens receiving groove of the zylonite coated frame.

2. The process of applying a composition 40 covering to a grooved metallic eye wire, consisting in forming flat non-metallic stock

into transversely curved shape to embrace the eye wire, and connecting the edges of the stock by a cementitious medium lying within the groove, whereby a continuous 45 non-metallic enclosing covering is permanently affixed to the grooved eye wire.

3. The process of applying a composition covering to a grooved metallic eye wire, consisting in exteriorly applying a split tube to 50 the eye wire and reversely crimping the central portion of the tube to cause the same to fit tightly into the groove of the eye wire.

4. The process of applying a composition 55 covering to a grooved metallic eye wire, consisting in exteriorly applying a split tube to the eye wire, reversely crimping the central portion of the tube to cause the same to fit tightly into the groove of the eye wire, 60 and stretching the composition covering around a size plate to sufficiently displace the reversely crimped material to produce a standard size lens receiving groove.

5. The process of applying a composition 65 covering to a grooved metallic eye wire, consisting in exteriorly applying a split tube to the eye wire, reversely crimping the central portion of the tube to cause the same to fit tightly into the groove of the eye 70 wire, and connecting the edges of the stock by a cementitious medium lying within the groove, whereby a continuous non-metallic enclosing covering is permanently affixed to the grooved eye wire.

75 In testimony whereof I have affixed my signature, in presence of two witnesses.

ELMER L. SCHUMACHER.
